(57) **CLAIM**

The ornamental design for an instrument panel for a motor vehicle, as shown and described.

DESCRIPTION

FIG. 1 is a front perspective view of an instrument panel for a motor vehicle thereof showing our new design;

FIG. 2 is a front view thereof;

FIG. 3 is a right side elevation view thereof;

FIG. 4 is a left side elevation view thereof; and,

FIG. 5 is a top plan view thereof.

Our design includes a mirror image of the embodiment depicted. The rear and bottom views form no part of the claimed design.
